UNITED STATES PATENT OFFICE.

LOUIS H. EILERS, OF CHICAGO, ILLINOIS.

GAME-TABLE.

No. 921,381.

Specification of Letters Patent.

Patented May 11, 1909.

Application filed October 22, 1908. Serial No. 458,988.

To all whom it may concern:

Be it known that I, LOUIS H. EILERS, a citizen of the United States, residing at Chicago, county of Cook, and State of Illinois, have invented certain new and useful Improvements in Game-Tables, of which the following is a specification.

My invention relates to improvements in game tables, and has for its object to provide the top of a table with the necessary means for conveniently keeping count of the number of points in a game of cards so arranged as to be plainly visible to all the players taking part in the game.

15 A further object of my invention is to provide an inclosed, dust-proof mechanism having a transparent center piece through which the registering dial may be easily read by the players.

20 Other objects will appear hereinafter.

With these objects in view, my invention consists in a game table comprising a dial and a plurality of independently operated pointers mounted on said dial for registering 25 the number of points that each player is making in a game. And my invention further consists in certain details of construction and arrangements of parts all as will be hereinafter fully described and particularly pointed out in the claim.

30 My invention will be more readily understood by reference to the accompanying drawings forming a part of this specification, and in which,

35 Figure 1 is a top elevation of my improved card table in its preferred form, Fig. 2 is an enlarged fragmentary view showing the central registering dial, Fig. 3 is a side elevation, and Fig. 4 is a detail section taken on the 40 line $x-x$ of Fig. 2.

Referring now to the drawings, 1 indicates a table top, and 2 a centrally disposed circular glass plate embedded therein. Table legs 3 and sides 4 are provided, and a rectangular box 5 is centrally located and secured to the top 1 beneath the glass plate 2. The dial on the top surface of the box 5 may have any suitable arrangement of numbers, but the same are preferably arranged as shown. The dial 45 pointers 6, 7, 8 and 9 are secured to the hubs of the bevel gears 10, 11, 12 and 13, respectively, said hubs being concentrically arranged and said gears being superimposed as shown. A central standard or support 14

on which the gears 10, 11, 12 and 13 are 55 adapted to rotate, is rigidly secured in the box 5 by means of the nuts 15. A collar 16 and a retaining nut 17 are provided on the support 14 to hold the gears on the same in proper position. Operating shafts 18, 19, 60 20 and 21 are provided with driving bevel gears 22, 23, 24 and 25, respectively. Bearing lugs 26 are secured to the box 5 by means of the screws 27, and the operating shafts 18, 19, 20 and 21 are journaled in said lugs and 65 in the sides of the box 5, said shafts being provided with handles or knobs 28. The driving bevel gears 22, 23, 24 and 25 are adapted to mesh respectively with the driven gears 10, 11, 12 and 13 and to turn the 70 pointers 6, 7, 8 and 9 when the knobs 28 are rotated by the players.

While I have shown what I deem to be the preferable form of my improved card table, I do not wish to be limited thereto, as there 75 might be many changes made in the details of construction and arrangement of parts without departing from the spirit of my invention.

Having described my invention what I 80 claim as new, and desire to secure by Letters Patent, is:

In a device of the class described, a table top, and a central glass plate embedded therein, a rectangular box secured to the 85 under side of said table top beneath said glass plate, a dial on said box visible through said glass plate, a centrally disposed support rigidly secured in the bottom of said box, and extending upwardly above the top of 90 the box, a collar on said support, a series of superimposed bevel gears resting one upon the others and supported by said collar, and having concentric hubs adapted to rotate on said support above said collar, dial pointers 95 secured to said hubs, and shafts journaled in said box and extending outwardly adjacent to the edge of the table top, and the bevel gears on said shafts adapted to mesh with and to drive said first-named bevel gears, respectively, substantially as described.

In testimony whereof I have signed my name to this specification in the presence of two subscribing witnesses.

LOUIS H. EILERS.
